DESIGN FOR AN ELECTRIC CLOCK

Louis Eickemeyer, Jersey City, N. J., assignor to
Joseph Gottlieb, Jersey City, N. J.

Application December 24, 1940, Serial No. 97,594

Term of patent 7 years

To all whom it may concern:

Be it known that I, Louis Eickemeyer, a citizen of the United States, residing at Jersey City, county of Hudson, and State of New Jersey, have invented a new, original, and ornamental Design for an Electric Clock, of which the following is a specification, reference being had to the accompanying drawing, forming part thereof.

Fig. 1 is a top plan view of an electric clock showing my new design; and

Fig. 2 is a front elevational view of the same.

I claim:

The ornamental design for an electric clock, as shown.

LOUIS EICKEMEYER.
